UNITED STATES PATENT OFFICE.

HENRY J. SHAVERS, OF GOLDSBORO, NORTH CAROLINA.

LUBRICATOR.

1,384,353.

Specification of Letters Patent. Patented July 12, 1921.

Application filed October 16, 1920. Serial No. 417,340.

To all whom it may concern:

Be it known that I, HENRY J. SHAVERS, a citizen of the United States, residing at Goldsboro, in the county of Wayne and State of North Carolina, have invented certain new and useful Improvements in Lubricators, of which the following is a specification.

My invention relates to a new and useful improvement in lubricators that are designed to force heavy oil and flake graphite to the cylinders of a locomotive.

An object of the present invention is to provide a lubricator wherein the oil and flake graphite is first poured into a funnel or large cup from which it is drawn into a reservoir in the form of a cylinder. In this cylinder is a piston which is to be under a slight pressure, and in the bottom of the cylinder is a port with an adjustable valve therein so that the amount of oil or graphite fed therefrom may be regulated as desired. From the first mentioned cylinder the oil is led into second cylinders from which it is forced out by compression to a pipe leading to the cylinder of the locomotive. These last two mentioned cylinders being operated by a small motor.

Still another object of the present invention is to provide a lubricator that is very compact in nature, highly efficient and capable of forcing the oil and graphite under compression to the cylinders of the locomotive.

Still another object of my invention is to provide a lubricator that is simple in operation, relatively cheap to manufacture and quickly and readily assembled.

With these and other objects in view as will be disclosed as the invention proceeds my invention consists of certain new and novel constructions and combinations of parts as will be hereinafter more fully described and pointed out in the drawings.

Figure 1 is a side elevation partly in section of my improved lubricator;

Fig. 2 is an end view partly in section; and

Fig. 3 is a detail of the worm and crank arms for driving the lubricator.

Referring now in detail to the several figures there is shown a base 1, on which is mounted a motor 2, although it is to be understood that any form of driving means may be employed.

A standard 3 is shown in which is

mounted the worm gear 4 which is driven by the worm 5 of the motor shaft.

Two crank arms 6 are revolved by the gear 4 to which cranks are secured and connecting rods 7, the same in turn being connected to the head 8 mounted on the slide bar 9.

This bar is supported at its one end by the standard 10 and at its other by the main housing 11 of the lubricator.

This housing 11 is in turn supported by the brackets 12 which are bolted to the base 1, as shown. Mounted in this housing are the two cylinders 13 and 14 to which are bolted the heads, 15 and 16. As the cylinders and heads and co-operating plungers are identical a description of one will suffice. Referring now in particular to Fig. 1 it will be seen that the head 16 extends inwardly for a greater portion of the cylinder, is provided with the packing rings 17 and is beveled at its inner end and provided with the projecting portion 18.

Operating in the cylinder is the hollow plunger 19 which is provided with the upper or inlet port 20 and with the larger outlet port 21 formed in its under surface. Connected with this plunger is the rod 22 which extends through the cylinder head 23 and the stuffing gland 24 and is fastened to the heretofore mentioned sliding head 8.

This hollow plunger snugly fits the head 16 so that when the same is operated it will compress the air in the plunger on its forward stroke and form a vacuum on its rearward or back stroke.

Extending through the lower portion of the cylinder is the port 25 and directly beneath the same is the check valve 26 secured to the coupling 27, in one side of which may be secured a jet pipe 28 while another pipe 29 leads to the cylinder of the locomotive. Also leading to this coupling 27 (Fig. 2) is the pipe 30 which is an auxiliary oil feed provided in case the operating plungers should be in any way damaged or become inoperative.

Referring again to the several figures, it will be seen that bolted to the housing 11 is the reservoir cylinder 31 in which is provided the piston 32, and entering the head of this cylinder is a pipe 33 for admission of a slight amount of steam. Secured at one side of this feed cylinder is the filling cup 34 with the valve 35 therein.

Extending through the base of the cylin-

der 31 is the central discharge opening 36 and across which is placed the valve 37 which is regulated by the movement of a handle 38 connected therewith.

5 Below this valve is placed a sight tube 39 so that the flow from the reservoir cylinder may be seen and regulated as desired. Beneath the valve 37 there is a small port 40 for the admission of a slight amount of air, 10 this port being connected to a check valve 51.

From the opening 36 extend the two feed channels 42 which lead to the two cylinders 13 and 14.

Also extending from the sides of the cylinder 31 are the two pipe lines 30' in which are the valves 43 and the sights 44 to which are connected the aforementioned pipes 30 so that an auxiliary feed is provided, if ever necessary.

20 The operation of the lubricator is therefore as follows: Oil and flake graphite or any other proper lubricant will be first poured in the cup 34 and the piston 32 raised which will draw the same into the cylinder 31, the valve 35 of course afterward closed. Steam will then be admitted to the pipe 33 so that a constant pressure will be kept on the piston.

The flow or feed of the lubricant will then 30 be regulated by first looking through the sight 39 and turning the handle 38 on the valve 37, until the proper feed is determined. The motor will be started and presuming the plunger 19 is in the position shown in 35 Fig. 1, as it is driven forward by the revolving of the worm gear 4 and its coöperating parts, the air and the oil that has passed through the several ports, and has been drawn by the rearward movement of the 40 plunger through the inlet port 20 into the plunger will be compressed. That is, as soon as the port 20 passes the projection 18 and the feed channel 42, and the piston will continue to compress until the discharge 45 port 21 alines with the port 25 when it will be forcibly blown into the pipe 29 leading to the cylinder of the locomotive. The jet pipe 28 being used if desired, to further force the lubricant to the cylinder.

50 As the plunger begins its rearward stroke the check valve 26 will close and a vacuum will be formed in the plunger until the inlet port 20 registers with the feed channel, when the oil will be drawn into the plunger and 55 the operation repeated. A small amount of air will be drawn from the port 40 along with the oil from the reservoir which is desirable. It will be seen that the flow of the lubricant is partly by gravity, partly by 60 pressure of the piston in the feed cylinder or reservoir, and partly by the vacuum caused by the return stroke of the plunger, thereby assuring a proper feed of the lubricant; while the flow to the cylinders of the locomotive is assured by subjecting the oil and

air to compression in the plungers and by providing a jet blower if found desirable.

From the foregoing it will be seen that I have provided a lubricator that is positive in action; may be quickly regulated as to 70 the proper feed, compact in nature, and efficient in service.

Also an auxiliary feed is provided so that in case of a break-down of the lubricator the cylinders of the locomotive may still be 75 sufficiently lubricated until the lubricator is repaired.

Many slight changes might be made in the arrangement and positioning of the parts without in any way departing from 80 the spirit and scope of the invention.

Having thus described my invention what I claim as new and desire to secure by Letters Patent is:—

1. A lubricator comprising a base, a cylinder on said base, a hollow plunger in said cylinder, said plunger provided with an inlet and outlet port and an inlet and outlet port in said cylinder, a reservoir for the lubricant, means for forcing the plunger inwardly and outwardly to draw the lubricant in said plunger, compress the air in said plunger and force the same with the lubricant from the plunger to the parts to be lubricated. 85

2. A lubricator comprising a base, two cylinders mounted on said base, hollow plungers mounted in said cylinders, a reservoir for the lubricant, means connecting said reservoir with said plungers, inlet and outlet ports in said plungers, inlet ports in said cylinders, outlet ports in said cylinders connecting with supply pipes to the device to be lubricated, means for operating said plungers to draw the lubricant in said plungers, compress the air in said plungers and force the lubricant into said supply pipes. 90

3. A lubricator comprising a base, cylinders mounted on said base, heads in said cylinders and extending into said cylinders, plungers operable in said cylinders and the said heads extending into said plungers, a reservoir for the lubricant, and ports extending from said reservoir to inlet ports formed in said plungers, said cylinders and plungers provided with outlet ports, pipes connected with the outlets in said cylinders and extending to the device to be lubricated, means for regulating the amount of lubricant to be fed to the plungers, and means 110 for operating the plungers to draw in the lubricant where the same is compressed with the air in the plungers and forced out by said compression when the outlet ports of the plungers register with the outlets in 115 said cylinders.

4. A lubricator comprising a base, cylinders mounted on said base, heads in said cylinders and extending within the cylinders, hollow plungers mounted in said cylinders 120

- provided with inlet and outlet ports, said cylinders provided with inlet and outlet ports, a reservoir for the lubricant, said reservoir provided with discharge openings 5 extending to the inlet ports in said cylinders and means in said reservoir for forcing the lubricant under pressure through said discharge opening, a motor for operating said plungers in said cylinders to thereby cause 10 the lubricant to be drawn in the plungers where the air is compressed and the lubricant blown therefrom when the outlet ports of the plungers and cylinders register.
5. A lubricator comprising a base, cylinders mounted on said base, hollow plungers provided with inlet and outlet ports therein mounted in said cylinders, said cylinders also provided with inlet and outlet ports, a reservoir for the lubricant mounted 20 above said cylinders and discharge feeds leading from said reservoir to the inlet ports in said cylinders, means for drawing the lubricant into said reservoir and for forcing it therefrom under pressure, means 25 for regulating the flow from said reservoir, discharge pipes leading from the outlets in said cylinders, means for operating said plungers to admit the lubricant to said plungers, compress the air in said plungers and 30 blow the lubricant from said plungers to the discharge pipes, when the outlets in said cylinders and said plungers register.
6. A lubricator for locomotives comprising a base, cylinders mounted on said base, hollow plungers provided with inlet and outlet ports therein mounted in said cylinders, said cylinders provided with inlet and outlet ports, a reservoir for the lubricant and means therein for exerting pressure on 40 the lubricant, discharge feed extending from
- said reservoir to the inlet ports in said cylinders, means inserted in the said feed for regulating the amount of feed to said plungers, discharge pipes leading from the outlet ports in said cylinders and provided with 45 check valves, a motor and means connected to said motor and to said plungers for operating the same to draw the lubricant into said plungers and expel the same under pressure to the discharge pipes when the outlet 50 ports in said cylinders register with the outlets in said hollow plungers, and additional means for forcing the lubricant through the discharge pipes.
7. A lubricator comprising a base, two 55 cylinders mounted on said base, hollow plungers operably mounted within said cylinders and provided with inlet and outlet ports, said cylinders also provided with inlet and outlet ports and discharge pipes connected to the outlet ports in said cylinders, a reservoir mounted above said cylinders, and provided with discharge openings leading to the inlet ports in said cylinders, 60 means for regulating the flow of the lubricant to the cylinders, an auxiliary feed leading from the reservoir direct to the discharge pipes, a motor provided with a worm on its shaft, a worm gear operated by said work and a sliding head operated by said gear, connecting rods extending from said head to said hollow plungers for operating the same to draw the lubricant into said 65 plungers, compress the air in said plungers and expel the lubricant under pressure to 70 the discharge pipes when the ports of the cylinders and plungers register.

In testimony whereof I affix my signature.

HENRY J. SHAVERS.
